CLAIM

The ornamental design for a shovel for removing debris from a gutter, as shown and described.

DESCRIPTION

FIG. 1 shows a front perspective view of the present invention;

FIG. 2 shows a side view of the present invention;

FIG. 3 shows a view from the other side of the present invention;

FIG. 4 shows a front view of the present invention; and,

FIG. 5 shows a rear view of the present invention.

The undisclosed bottom view of the pan element of the shovel is planar and unornamented.

FIG. 1

FIG. 2

FIG. 3

FIG. 4

FIG. 5
